CLAIM

The ornamental design for a bottle, as shown and described.

DESCRIPTION

FIG. 1 is a top, front perspective view of a bottle in accordance with a first embodiment of our new design; FIG. 2 is a bottom, rear perspective view thereof; FIG. 3 is a front elevation view thereof; FIG. 4 is a rear elevation view thereof; FIG. 5 is a right side elevation view thereof; FIG. 6 is a left side elevation view thereof; FIG. 7 is a top plan view thereof; FIG. 8 is a bottom plan view thereof; FIG. 9 is a top, front perspective view of a bottle in accordance with a second embodiment of our new design; FIG. 10 is a bottom, rear perspective view thereof; FIG. 11 is a front elevation view thereof; FIG. 12 is a rear elevation view thereof; FIG. 13 is a right side elevation view thereof; FIG. 14 is a left side elevation view thereof; FIG. 15 is a top plan view thereof; and, FIG. 16 is a bottom plan view thereof.

The broken lines in the figures show portions of the bottle that form no part of the claimed design. The dash-dot lines indicate an unclaimed boundary and form no part of the claim.

1 Claim, 14 Drawing Sheets
